FLOOR FURNACE

Benjamin F. Stephens, Tulsa, Okla.

Application December 24, 1937, Serial No. 181,555

3 Claims. (Cl. 126—116)

This invention relates in general to furnaces, and while the principles thereof may be embodied in furnaces of various characters, the particular embodiments here disclosed as illustrative of my invention is what is commercially known as a floor furnace of the gas burning type.

In localities where intensely cold temperatures prevail only infrequently many residences, particularly of the cheaper type, are not provided with basements or with steam or hot-water heating equipment. On the contrary, floor furnaces of the hot air type are utilized which set below the floor level of the house and are customarily suspended from the floor joists. To accommodate such a furnace, it is usually necessary to excavate a shallow hole below the ground level beneath the house into which the lower end of the furnace extends.

Great difficulty and inconvenience is occasioned, however, with this type of installation when, as a result of a heavy rainfall, water collects in the hole into which the furnace extends, since such water flows into the open lower end of the furnace casing submerging the burners and extinguishing the flame. Furthermore, the fuel gas escaping from the extinguished burners accumulates in the combustion chamber and the flues, and when an attempt is made to light the burner with a torch or flame, serious explosions and fires are frequently caused.

One of the primary purposes of my present invention is to provide a furnace of the floor type which will be hermetically sealed to a height well above the ground line so that any water accumulating in the excavation into which the furnace extends will be precluded from entering the furnace casing and extinguishing or in any way interfering with the operation of the burners.

Another object of my invention is to provide a furnace which will be highly efficient in operation so as to utilize for heating purposes the maximum number of heat units liberated by the burner. With this end in view, my invention contemplates a furnace in which the products of combustion are caused to travel in a tortuous path from the combustion chamber to the stack flue so as to enable the delivery of a maximum number of heat units therefrom to the surrounding circulating air to be utilized for heating purposes.

Other objects and many of the inherent advantages of my invention should be readily appreciated as the same becomes better understood by reference to the following description when considered in connection with the accompanying drawings.

Referring to the drawings:

Fig. 1 is a longitudinal, vertical sectional view through a furnace constructed in accordance with my invention;

Fig. 2 is a horizontal sectional view taken on the 5 staggered line 2—2 of Fig. 1;

Fig. 3 is a vertical, transverse sectional view on the staggered line 3—3 of Fig. 1; and

Fig. 4 is a perspective view, partially broken away, of the main portion of my furnace structure with the casing removed.

Referring to the drawings more in detail, reference character 5 indicates a casing of rectangular shape formed of sheet metal or other suitable impervious material adapted to be introduced 15 through an opening 6 in a floor 1 and suspended in operative position, as illustrated, between the floor joists 8 to which, if desirable, it may be anchored by screws or other fastening means. The vertical portion of the casing comprises the 20 side walls 9 and 11 and the end walls 12 and 13 sealed at their joints to prevent water leakage therethrough, and the lower end of the casing is closed by a bottom 14 also sealed to the side and end walls so as to provide a water tight casing 25 structure.

Within the casing there is disposed an elongated, preferably rectangular, combustion chamber 15 comprising the end walls 16 and 17 resting upon the bottom 14, the side walls 18 and 19, the 30 bottom 21, and the top 22. The side walls comprise the inclined portions 23 and 24 which narrow the upper portion of the combustion chamber so that the upper walls of this portion are offset inwardly with respect to the side walls of the lower 35 portions. The top wall 22 is provided with an opening 25 normally closed by a removable cap 26 through which access to the interior of the combustion chamber for the purpose of igniting the pilot burners with a torch or the like may be 40 had. The bottom 21 is provided with elongated openings 27 in proximity to the burner, to be later described, and the space beneath and between these openings is enclosed by a depressed wall 28 providing an air passage 29 for the supply 45 of air to the burner. This passage, as will be apparent from Figs. 2 and 4, is extended laterally beyond each side wall of the combustion chamber to form a closed conduit having upwardly opening nipples 31 for connection with conduits 32 which extend upwardly a substantial distance 50 above the casing bottom and, in the form shown, at least one-half the height of the casing where they open to atmosphere through openings 33 formed in the side walls of the casing. A plurality 55

of air supply conduits is thereby provided for conducting air from a level considerably above the ground line outside the casing to the vicinity of the burners for combustion purposes.

5 The burners 34 are carried by a suitable manifold 35 mounted in the bottom wall of the combustion chamber, as shown in Fig. 1, and gas or other fuel is supplied to these burners through a pipe 36 equipped with a control and shut-off valve 37 adapted to be manipulated from a point in proximity to the floor level by a suitable rod 38. One or more pilot burners 39 are mounted in proximity to the main burners, the pilot burners receiving their fuel supply through a pipe 41 also equipped with a shut-off and control valve 42 operable through a rod similar to rod 38. 10 The products of combustion rising from the burners flow from the combustion chamber through openings 43 and 44 at the top and near each end of the chamber. For the purpose of retarding the escape of the products of combustion so that more heat units may be given off, the upper portion of the combustion chamber is equipped with a pair of transversely disposed, downwardly inclined baffles 45 and 46 around which the products of combustion escape, as indicated by the arrows in Fig. 1. From the openings 43 and 44 the products of combustion enter a pair of transversely extending flue passages 47 and 48, respectively, both of which communicate at their outer ends with heating chambers 49 and 51 disposed laterally of, parallel with, and spaced from the narrow upper portion of the combustion chamber 15. At their rear 15 ends these chambers communicate with an outlet box 52 through the passages 53 and 54, respectively, the outlet box being centrally connected with a stack flue 55. For the purpose of further retarding the direct escape of the products of combustion and thereby augmenting the delivery of heat units from these products, the heating chambers are provided with the downwardly inclined walls or baffles 56 and 57, respectively, which cause the products issuing from the flue 48 to flow to the forward ends of the respective heating chambers and then down and back to the discharge passages 53 and 54. During the travel of the products of combustion around the baffles 45 and 46, through the flues 47 and 48, and through the heating 20 chambers 49 and 51 and around the baffles therein, ample opportunity is afforded for the delivery of heat units from the products of combustion to the surrounding air which carries the heat units upwardly from the furnace into the dwelling. It will be observed that the spacing of the heating chambers from the upper portions of the combustion chamber provides passages between these chambers through which the air being heated flows while receiving heat simultaneously from both chambers.

The intervening space between the heating chambers and the outside casing is divided by a jacket into a down-draft passage 58 and an up-draft passage 59. The jacket comprises a rectangular outer shell 61 and an inner shell 62 spaced therefrom so as to provide for live air insulation between the spaced shells. The upper portion of shell 61 is of truncated form, as indicated at 63, to direct the heated air centrally upwardly through the usual grill or grating 64, while the cold air along the floor of the building is drawn downwardly through the outer margin of the grill into the down-draft passage 58 at 25 the bottom of which it turns inwardly and up-

wardly to be heated by the combustion and heating chambers and delivered from the furnace back into the building.

From the foregoing it should be manifest that I have provided a furnace which is very efficient in operation because of the manner of handling and directing the products of combustion through the furnace to obtain the maximum dissemination of heat therefrom and that the furnace, because it is completely sealed below the air intake openings for the combustion air which are located at least midway the height of the casing, will not be affected by surrounding water so long as the water level does not rise to the height of the air intake openings. The furnace may, therefore, be suspended in an excavation extending below ground level without danger of the burner becoming submerged and extinguished by any seepage or flow of water into the excavation. Since the air intake openings 33 are always located well above the ground line, the possibility of flame extinguishment and the danger of explosions and fires resulting therefrom, all occasioned by the presence of water in the furnace casing, are entirely eliminated by my invention.

While I have shown and described for illustrative purposes that embodiment of my invention which at present seems preferable, it should be understood that the structural details disclosed may be varied within wide limits without departing from the essence of my invention as defined in the following claims.

I claim:

1. A furnace comprising a casing composed of side walls and a closed bottom, a combustion chamber located therein, a burner in said combustion chamber, a partition wall dividing the space between the combustion chamber and the casing into a cold air down-draft passage and a hot air up-draft passage, means for conducting the products of combustion from said chamber in a tortuous path surrounded by said partition to a delivery point outside of said casing, a combustion air inlet opening in said casing located a substantial distance above the level of said burner, and conduit means for conducting air from said air inlet opening to said combustion chamber, said casing below the inlet of said conduit being sealed to preclude the entrance of water thereto.

2. A furnace comprising a casing having vertical side walls and a closed bottom wall, a heating unit in said casing including a combustion chamber spaced from the bottom wall of said casing, a burner in said combustion chamber, a combustion air inlet opening in said casing located a substantial distance above the level of said burner, an air inlet conduit communicating at one end with said opening and extending downwardly within the casing and beneath the combustion chamber and communicating at its opposite end with the combustion chamber in proximity to said burner, said casing being sealed below said air inlet opening to preclude the entrance of water thereto, means for retarding the flow of combustion gases through said heating unit, a stack flue, and means for establishing communication between said combustion chamber and said stack flue.

3. A furnace comprising a casing including an upright side wall and a bottom wall, a heating unit in said casing having a combustion chamber comprising an upright wall and a top wall, the lower end of said combustion chamber being

5 spaced from the bottom wall of said casing, a burner in said combustion chamber, a jacket in said casing surrounding said heating unit and dividing the space between said casing and said heating unit into a cold air down-draft passage and a hot air up-draft passage, a combustion air inlet opening in the side wall of said casing at a height substantially above the level of said burn-

er, an air conduit having an upright portion between said casing and said jacket for conducting air from said air inlet opening to said combustion chamber, said casing being sealed below said air inlet opening to preclude the entrance of 5 water thereinto.

BENJAMIN F. STEPHENS.
